SELF-CLEANING ELECTRICAL
PRECIPITATOR

Irvine A. Yost and Edward H. R. Pegg, Lakewood,
Ohio, assignors to Westinghouse Electric &
Manufacturing Company, East Pittsburgh, Pa.,
a corporation of Pennsylvania

Application November 18, 1942, Serial No. 466,020

4 Claims. (Cl. 183—7)

Our invention relates to improvements in electrical precipitators for electrostatically removing foreign particulate matter, hereinafter termed dust or dust-particles, from a flowing gas; which precipitators are of a class having dust-precipitating means comprising a plurality of individually distinct, structurally similar, dust-precipitating sections which are moved successively in a predetermined endless path through a gas-cleaning portion of the precipitator in which the dust-precipitating sections are utilized for gas-cleaning, and through an electrode or plate-cleaning portion of the precipitator, in which the dust-precipitating sections are successively subjected to a cleaning action intended to remove the accumulated collected dust from the sections by the use of a viscous liquid. Each section comprises a plurality of spaced relatively insulated and uninsulated dust-collecting electrodes or plates. The sections are arranged compactly along the endless path and are successively passed from the gas-cleaning portion into the plate-cleaning portion and then back to the gas-cleaning portion of the precipitator. Precipitators of this class are described in Patent No. 2,212,885 of August 27, 1940, to H. W. Pound et al. and in patent-application Serial No. 431,391 of G. W. Penney, filed February 18, 1942, which matured on January 5, 1943, into Patent No. 2,307,603.

An electrical precipitator-unit to which our invention more particularly pertains comprises a dust-precipitating means, as aforesaid, in the form of a curtain having its individually distinct sections movable one after the other in an oblong endless path having its long sides spaced from each other longitudinally along the gas-stream, and extending transversely across the gas-stream. An endless path of this type is provided with end portions out of the gas-stream, along which each section is moved for reversing its direction of travel. By arranging the endless path vertically, each section of the curtain can be conveniently and automatically cleaned while in an end portion of the endless path by a viscous liquid which is generally oil, and is so designated hereinafter.

In use, such an electrical precipitator-unit has relatively insulated elements, including the relatively insulated and uninsulated dust-collecting plates of the movable sections, which are oppositely charged by relatively high voltages. Flashovers or spitting occasionally, and sometimes frequently, occur between such oppositely charged elements; being caused generally by a lump of collected relatively conducting dust reducing the gas-insulation between the elements, or by large relatively conducting dust-particles trapped or

flowing between oppositely charged dust-collecting plates. The bridging matter is usually quickly burned up or burst so that such a flashover or spitting is usually momentary. The equivalent of flashovers in the form of arcs may also occur when charging circuits are interrupted or about to be made. Such a flashover, due to circuit-arcs, may persist until the arcing terminals of the circuit are moved to discourage or extinguish the arc. If the circuit is being interrupted, the arc-extinction will take place when the terminals are separated a sufficient distance; and if the circuit is being completed, the arc extinction will take place when the terminals are in conductive engagement or contact. Momentary flashovers are, as a rule, of too short duration to ignite a combustible oil or oil-soaked collected dust; but flashovers due to circuit-make or -break may, under certain conditions, be of sufficiently long duration to cause the combustible oil to reach inflammable temperatures.

It is accordingly a primary object of our invention to provide an electrical precipitator of a class described, utilizing oil for either cleaning the dust-precipitating sections or coating the plates thereof with a layer of oil for causing dust adherence, in which fire hazards are minimized. To this end, our invention is directed to reducing to a minimum the quantity of cleaning oil in the precipitator and to reducing or eliminating conditions giving rise to excessive circuit-arcs.

A specific mode indicating the application of our invention in a preferred form is explained in the following description thereof which is limited to the essential parts necessary for an understanding of our invention. The description is to be taken in connection with the accompanying drawings in which parts have been omitted from some views in the interest of clarity. In these drawings, in which like numerals refer to like parts:

Fig. 1 is a vertical sectional view of a precipitator-unit embodying our invention;

Fig. 2 is a detail thereof;

Fig. 3 is a partial vertical sectional view, transverse to Fig. 1, of the lower part of the precipitator-unit with the dust-precipitating curtain removed;

Fig. 4 is a horizontal sectional view of a lower part of the precipitator-unit; and

Fig. 5 is a control system for operating the plate-cleaning means of our precipitator.

Referring more particularly to the drawings, the precipitator-unit comprises a vertical housing indicated in its entirety by the reference numeral 2. Such a housing is adapted to be placed in a gas-conduit or duct means, or be part there-

of, in which a substantially horizontal gas flow is established in any suitable manner. The housing is provided with suitable openings for the gas-stream.

For electrostatically cleaning the gas, the housing carries an ionizing means 4, and supports a dust-precipitating curtain 6 following the ionizing means 4 in the direction of gas flow which is indicated in Fig. 1 by the full line arrows. The ionizing means 4 comprises a plurality of spaced ground electrodes 8 between which are insulatedly supported ionizing wires 10. The dust-precipitating curtain 6 is disposed within the housing 2, and has the form of a vertical endless oblong with spaced parallel long sides between a gas-inlet 12 immediately in back of, or on the downstream side of, the ionizing means 4, and a gas-outlet 14 in back of the curtain. The long sides of the dust-precipitating curtain extend above and below the upper and lower ends, respectively, of the gas-inlet and gas-outlet and project slightly beyond the other sides thereof. The dust-precipitating curtain comprises a plurality of like dust-precipitating sections 16.

Each dust-precipitating section comprises a like number of spaced alternately relatively insulated and uninsulated plates, the insulated plates being designated by the reference numeral 18 and the uninsulated plates being designated by the reference numeral 20. The insulated plates of each section are electrically conductively connected together by a jumper means 22; and the uninsulated or grounded plates 18 are electrically connected together by a similar jumper means 24 (Figs. 1 and 4). The jumper means 22 and 24 are spaced transversely along a section and provided with contacts 26 for the insulated plates 18 for the uninsulated plates, by transversely meaning transverse to the direction of gas-flow and to the direction of movement of the curtain 6. The contacts 26 and 28 for each section are transversely aligned.

The dust-precipitating sections 16 are arranged side by side, being mounted on a pair of sprocket chains 30 along the upright end walls of the housing, which mesh with sprocket wheels 32 at the top of the precipitator-unit and sprocket wheels 34 at the bottom of the precipitator-unit. The sprocket chains 30 are preferably constructed of removable small links so that a relatively large number is associated with each section. The sprocket wheels 32 are mounted on a driving shaft 36 having an end protruding beyond an end wall of the housing 2, to which is secured a driving means for moving the dust-precipitating curtain 6. The lower sprockets 34 are fixed on a vertically adjustable rotatable guide shaft 38.

The driving means for driving the dust-precipitating curtain 6 comprises a continuously rotating motor 40 (Fig. 5) connected to a speed-reducing gearing box 42 which in turn drives the shaft 36 through any suitable mechanical connection. The gearing within the box 42 includes any suitable means for changing the continuous rotation of the motor 40 to intermittent motion for relatively rapidly intermittently moving the dust-precipitating curtain 6 a predetermined distance each time between suitable intervals of a few minutes or so.

Each section 16 is preferably provided with one contact movable 26 and one movable contact 28, the corresponding contacts 26 or 28 of adjacent sections being substantially aligned in the direction of movement of the curtain 6; such contacts being separated a distance equal to the distance the curtain is moved each time.

Contact bar means are provided which the contacts 26 and 28 slidably engage during their movement through the gas-cleaning portion of the housing 2 so that the insulated and uninsulated plates across the gas-stream passing through the housing can be oppositely charged for providing the necessary dust-precipitating field between adjacent plates. Such bar means comprises a narrow bar 46 which the contacts 26 of the sections which are at the front side of the dust-precipitating curtain engage; and a narrow bar 48 of slightly greater length than the bar 46, which the contacts 26 at the back side of the curtain engage. The bars are insulatedly supported by the housing 2 in any suitable manner. Such supporting means may comprise insulators 50 supporting conducting bars 52 which position and conductively connect the contact bars 46 and 48. An insulated conductor 54, connected to a terminal of a unidirectional source of power, is secured to a bar 52.

The contacts 28 for the uninsulated plates engage an oblong contact bar means 56, more particularly shown in Fig. 2, which follows the path of the contacts, and is conductively connected to the metallic housing 2 and thereby grounded. The other terminal of the aforesaid source of power is also grounded.

The sprocket chains 30 are of a length which is an integral number of times the distance between consecutive contacts 26 or 28; and initially the curtain is arranged so that the contacts 26 of the sections 16 next to be placed in the gas-stream or just moved from the gas-stream are an adequate distance from the conducting bars 46 and 48 for preventing an arc-over; and the contacts 26 of the sections 16 in the gas-stream are in full engagement with the bars 46 and 48.

In the operation of the parts thus far described, the motor 40 intermittently drives the shaft 36 in a direction indicated by the broken line arrow of Fig. 1, moving the curtain 6 intermittently every few minutes a distance equivalent to the spacing between consecutive contacts 26 or 28, so that the positions and number of contacts 26 associated with the insulated contact bar means 46 and 48 will always be the same. The length of the bars 46 and 48 is so chosen that when the dust-precipitating curtain 6 is moved, an oncoming section 16' will replace the section 16", so that the movable contacts 26' of the section 16' will replace the movable contacts 26" of the section 16" in full engagement with the bar 46. A similar operation takes place with respect to the contacts 28 approaching the bar 48. The contacts 26 leaving the bars 46 and 48 move from full engagement with the bars to adequate separation therefrom for extinguishing any circuit-breaking arc. Consequently, at no time while the curtain is stationary will any of the contacts 26 be removed only such a short distance from either bar as would permit a continuing-arc until the movable contact is later moved to an arc-interrupting position leaving a bar, or to full engagement with a bar which it is approaching.

For cleaning the plates of a dust-precipitating section, a pipe 58 is provided between the sprocket wheels 34 below the shaft 36. The pipe is provided with a plurality of downwardly directed nozzle 60 adapted to discharge a spray of oil across and between the plates of a section

therebelow. A second pipe 64, at the side of the pipe 58, has a plurality of nozzles 66 through which a gas-blast can be discharged for blowing excess oil from a cleaned section therebelow.

In the lower plate-cleaning portion of the housing 2, oil discharged through the nozzles 60 washes collected dust from the plates of the section therebelow. The quantity of oil discharged is preferably such that the resulting oil-streams will have sufficient force to flush the collected dirt from the dust-collecting plates by an action akin to rapid erosion. Thus, the dirt layer is completely removed and the plates are entirely cleaned. When a cleaned section moves to a position under the nozzles 66, the plates thereof are subjected to a gas-blast which removes excess oil drops from the plates, leaving only a thin film thereon. The gas-blast leaving the spaces between the plates is directed toward a bottom 10 for the housing which also functions as a liquid catching basin for the oil discharged through the nozzles 60. Oil drops in the gas-blast hitting this basin stick to it and any other oil drops which may be carried along with the gas-blast are caught in a filter 72 across a gas-exit at the back side of the housing 2. Preferably, the gas used for the gas-blast is cleaned gas so that the exhausted gas passing through the filter 72 may be discharged directly back into the cleaned gas-stream. Baffle means 73 may be provided to limit the tendency of gases from the gas-blast to flow directly to the outlet 14 rather than through the filter 72.

An important feature of our invention resides in limiting any accumulation of washing oil in the bottom of the precipitator-unit. To this end the basin 10 is provided with a drain 74 connected to a downwardly sloping pipe 76 which, in turn, is connected to a drain pump 78 which pumps used liquid into a tank or reservoir 80. A supply pump 82 pumps liquid from this reservoir to the supply pipe 58, through an oil filter 84. A baffle 86 in the reservoir 80 deflects liquid pumped by the drain pump 78 towards the bottom of the reservoir.

It is not necessary to have a continuous flow of liquid or gas through the pipe 68 or 54, respectively. For timing these operations the gearing 42 may drive a drum controller 88 in predetermined relation to the movement of the dust-precipitating curtain 6. The drum controller 88 has a contact 90 adapted to engage a brush 92 for causing operation of the supply pump 82 from a time just before the curtain begins to move until a short time after movement has been completed. A contact 94 on the drum controller 88 is adapted to engage a brush 96 for causing operation of the drain pump 78 while the operating pump 82 is operating and for a short time thereafter to insure a complete draining of discharged oil from the basin 10. A contact 98 on the drum controller 88 is adapted to engage a brush 100 for causing the opening of a valve 102 in the gas-supply line to the gas-blast pipe 64; the gas-blast being continued for a short time after the supply pump is stopped. The gearing 42 is arranged to drive the drum controller 88 through one complete cycle in synchronized relation with each intermittent movement of the dust-precipitating curtain 6.

As an alternative modification for eliminating entirely any circuit-making and circuit-breaking of the charging circuit to the plates of the dust-precipitating sections, an insulated oblong con-

tact bar means similar to the bar means 56 may be substituted for the bars 46 and 48.

While we have described our invention which we believe at present constitutes the preferred form of embodiment, it is obvious that many modifications may be made therein and equivalent parts substituted.

We claim as our invention:

1. An electrical belt-type dust-precipitator for cleaning a gas-flow, comprising, in combination, a plurality of dust-precipitator sections, each comprising a plurality of spaced facing relatively insulated and uninsulated plate-electrodes, positioning means for intermittently moving said sections step-by-step through a plurality of successive gas-cleaning positions along a substantially straight side of an oblong endless path, then through an electrode-cleaning portion at a return bend of said path, and then through a plurality of successive gas-cleaning positions along the other substantially straight side of said path, and circuit means for oppositely charging the adjacent plate-electrodes of each section in each of its positions, said positioning means causing said sections to move a predetermined distance which is an aliquot part of the length of said path, for causing the sections to repeatedly occupy the same positions in consecutive passages of said path.
2. An electrical belt-type dust-precipitator for cleaning a gas-flow, comprising, in combination, a plurality of dust-precipitator sections, each comprising a plurality of spaced facing relatively insulated and uninsulated plate-electrodes, positioning means for intermittently moving said sections step-by-step through a plurality of successive gas-cleaning positions along a substantially straight side of an oblong endless path, then through an electrode-cleaning portion at a return bend of said path, and then through a plurality of successive gas-cleaning positions along the other substantially straight side of said path, and circuit means for oppositely charging the adjacent plate-electrodes of each section in each of its positions, said positioning means comprising an insulated contact bar-means extending along the complete path of movement of said sections, and a plurality of spaced contacts, each fastened to one of said sections, slidably continuously engaging said bar-means.
3. An electrical belt-type dust-precipitator for cleaning a gas-flow, comprising, in combination, a plurality of dust-precipitator sections, each comprising a plurality of spaced insulated plate-electrodes, means for intermittently moving said sections step-by-step through a plurality of successive gas-cleaning positions along a substantially straight side of an oblong endless path, then through an electrode-cleaning portion at a return bend of said path, and then through a plurality of successive gas-cleaning positions along the other substantially straight side of said path, circuit means for charging said plate-electrodes of each section in each of its gas-cleaning positions, said positioning means causing said sections to move a predetermined distance which is an aliquot part of the length of said path, for causing the sections to repeatedly occupy the same positions in consecutive passages of said path, and pipe-means, comprising a fixed member in said electrode-cleaning portion inside the periphery of said path, for removing precipitated dust from each section when such section is in cleaning association with said member.
4. An electrical belt-type dust-precipitator for

cleaning a gas-flow, comprising, in combination, a plurality of dust-precipitator sections, each comprising a plurality of spaced facing relatively insulated and uninsulated plate-electrodes, positioning means for intermittently moving said sections step-by-step through a plurality of successive gas-cleaning positions along a substantially straight side of an oblong endless path, then through an electrode-cleaning portion at a return bend of said path, and then through a plurality of successive gas-cleaning positions along the other substantially straight side of said path,

5 circuit means for oppositely charging the adjacent plate-electrodes of each section in each of its positions, a pipe-means in said electrode-cleaning portion, inside said oblong path, for discharging a treating liquid into a section associated therewith in said electrode-cleaning portion, and means for causing said pipe-means to periodically discharge said treating liquid in a predetermined time relation to the intermittent movement of said sections.

10
